UNITED STATES PATENT OFFICE.

WILLIAM B. CLOSE, OF PORTLAND, INDIANA.

PISTON-RING-GRINDING LATHE.

Application filed May 28, 1921. Serial No. 473,394.

To all whom it may concern:

Be it known that I, WILLIAM B. CLOSE, a citizen of the United States, residing in the city of Portland, in the county of Jay, State 5 of Indiana, have invented a new and useful Piston-Ring-Grinding Lathe, of which the following is a full, clear, and comprehensive specification and exposition, the same being such as will enable others to make and use 10 the same with exactitude.

The object of my present invention, broadly speaking, is to provide a piston ring grinding machine which will be simple in character, positive and precise in its results, 15 easily operated and controlled, and which can be manufactured and sold at a comparatively low price.

Heretofore it has been customary to completely finish the manufacture of piston 20 rings before they are placed in operative position in the piston-head, and the placing of the rings in such position manifestly causes the rings to be unduly strained and they frequently become permanently untrue and 25 therefore do not give the best results in practice, therefore the specific object of this invention is to finish the formation of piston rings after they are in their final position in the piston, but before placing them in 30 their cylinders, in order that they will be absolutely true and properly fitted each to the particular place it is to operate in, thereby obtaining the best possible results.

Other minor objects and particular advantages of my invention will suggest themselves in the course of the following description, and that which is new and useful will be correlated in the appended claims.

The preferred means for carrying out the 40 principles of my invention in a practical manner is shown in the accompanying drawings, in which—Figure 1 is a top plan of the entire lathe in which my invention is incorporated. Figure 2 is a front 45 side elevation of the same. Figure 3 shows the grinder and the grinder-yoke in elevation, also showing the tracks on which carriages are mounted. Figure 4 is a top plan view of the grinder and the work holder as 50 in operative position. Figure 5 is also a top plan view of the grinder and showing certain parts of the work holder in horizontal section. Figure 6 is similar to Fig. 5 except that the piston is shown in central 55 horizontal section. Figure 7 is a side ele-

vation of a portion of a cylinder showing the piston rings to be operated upon. Figure 8 is a perspective view of one of the dogs for holding the rings in place to be operated upon.

Similar indices denote like parts throughout the several views; in order that the construction, the operation, and the advantages of my invention may be more fully understood and appreciated I will now take up a 60 detailed description thereof, in which I will set forth the invention as fully and as comprehensively as I may.

Referring now to the drawings in detail: Numeral 1 denotes the pedestal which supports the lathe above a floor (not shown). Carried by the pedestal are the two horizontal parallel tracks 2 and 3, such as are 65 common to lathes.

Mounted on the left ends of said tracks is 70 the propeller carriage 4 which has the upwardly extending brackets 5 and 6 which carry the drive-shaft 7 in the usual manner.

Secured on the shaft 7 are the pulleys 8, 9 and 10 which are adapted to receive thereon the belt 11, whereby the shaft may be 75 revolved by power and at various speeds as desired.

To the right of the bracket 6 there is a head 12 secured on the end of the shaft 7, 80 and said head has a pin 13 projecting to the right and located at one side of the center thereof. The head 12 has a peripheral channel 14 formed in its right-hand edge for the purpose hereinafter stated.

The main carriage comprises the two side-rails 15 and 16, which are connected by the cross member 17. The side rails 15 and 16 are mounted to slide on the tracks 2 and 3, the same being geared to be moved to the 85 right and the left on said tracks by turning the hand-wheel 18.

Adjustably mounted on the right-hand portion of the tracks 2 and 3 is the minor work-support carriage, comprising the base 100 19 and the top 20, the latter carries the horizontal stem 21 in which latter is a screw shaft whose left end terminates at the pointed centering tool 22. The said screw is adapted to be turned by the handle 23 in 105 order to move the tool 22 to the right or left to adjust it to the work. The stem 21 is adjustably secured in the top 20 by means of the handle 24.

Numeral 25 denotes the yoke, whose feet 110

26 and 27 are adjustably secured on the side-rails 15, and 16, respectively, by means of the respective pairs of bolts 28 and 29.

The central portion of the yoke 25 is enlarged, and it has a comparatively large aperture formed therethrough, which aperture is to receive the end of the cylindrical shell 30 therein, whereby said shell 30 may be removed and replaced. The purpose of 10 making the shell removable is that a number of such shells 30 may be provided, one for each size ring or piston to be ground, by which it is evident that simply choosing the proper shell for the particular rings to be 15 ground one is enabled to use the machine for all sizes of rings by simply selecting the proper shell for the rings to be ground.

Numeral 32 denotes an ordinary piston-head, having channels therearound in which 20 are placed the piston-rings 33. The inside diameter of the shell 30 is only infinitesimally more than is the outside diameter of the head 32, in order that the head may slide snugly therein, and the channel 25 14 is of the same depth as is the thickness of the wall of the head 32, whereby the outside diameter of the head 12 is precisely the same as is the outside diameter of the head 32 by which it is evident that they may be arranged as shown in Fig. 5, that is tandem.

One end of the head 32 is made closed, the other end being open, and a crank-pin 36 extends across the interior of the head, as is shown in Fig. 6, the same being ordinary 55 construction.

As is well known, the rings 33 are cut on an angle, thereby forming two sharp points at the ends of the rings. In order to hold 40 said rings, whereby they may be operated upon, I employ a securing dog for each ring, and in order that the said dogs may be employed I cut off one of the corners of the ring, in amount equal to the size and shape 45 of the stem 34 of the body 35 of the dog shown in Fig. 8. This permits the dog to be placed in operative position with the ends of the ring contacted with each other, as 50 shown in Fig. 5. The shape of the body 35 causes it to act as a locking cam, whereby 55 when the rings are clamped to closed position with the periphery thereof flush with the periphery of the head 32 the dogs will lock their respective rings from rotation, whereby they may be properly operated upon.

When the dog, shown in Fig. 8, is in operative position, as in Figs. 5 and 7, the ring 33 will be prevented from turning in its channel in the head 32 as the edges of the 60 body 35 will engage the sides of the channel in the head thereby preventing movement of the dog, and then of course the stem 34 of the dog will prevent the ring 33 from turning in its channel. In other words: By 65 reason of the stem 34 being located at the

end portion of the body 35 it is evident that the inclination of the ring to turn in its channel will cause the dog to act as an eccentric, that is causing it to twist whereby its sharp edges will engage both walls of 70 the channel and thereby locking the dog and thereby preventing the ring from turning in its channel.

Extending up from the side rail 16 of the main carriage is the bracket 37 which supports the table 38 which in turn supports the elongated horizontal bearing 39 in which latter is revolvably mounted the grinder shaft 40. 75

Detachably secured on the left end of the shaft 40 is the abradant wheel 41 by which the grinding is to be done. Also mounted on the table 38 is the electric motor 42, the same being connected with the shaft 40, by means of the shaft coupling 43. 80

Electric current to operate the motor is supplied by means of the wires 44 and 45, which lead to a source of power.

The table 38 is so mounted that it may, 90 be moved forward and rearward by simply turning the crank handle 46.

It should be understood that a notch 47 is formed through the shell 30 opposite to the wheel 41 and corresponding in width with the width of said wheel, into which the 95 edge of said wheel may enter as shown in Figs. 4, 5 and 6.

Operation: In practice the rings 33 to be ground are placed in their respective channels in the piston-head, after which the 100 head 32 is placed in position in connection with the head 12, that is with the open end of the head 32 toward the head 12, with the edge of the head 32 fitting in the channel 14, which of course will bring the pin 13 to where it will engage the pin 36 when the parts are rotated. The next operation will be to revolve the wheel 18 to cause the main carriage to move to the left, thereby causing the shell 30 to slide over the head 12, and partly cover the head 12 thereby enclosing the head 32. Next the crank 23 is to be revolved to cause the tool 22 to move to the left until the point of the tool 22 engages the center of the closed end of 110 the head 32, as in Fig. 6.

It of course is to be understood that the main carriage has been moved until the ring 33 to be ground is exposed at the notch 47, that is a portion thereof registers with said notch. 120

After the above mentioned arrangements have been made, then the power is to be applied to operate the belt 11, which of course will revolve the head 12, and by reason of the pin 13 engaging with the crank-pin 36 it is evident that the head 32 will be revolved slowly within the shell 30, and will carry with it the piston-rings 33 which are secured thereto by the dogs, (Fig. 8). 130

The electric current may now be turned into the motor 42 which is geared to revolve the abradant wheel 41 at a comparatively high rate of speed.

5 The operator may now turn the crank 46 to move the table 38 slowly forward, finally bringing the revolving wheel 41 into grinding contact with the slowly revolving ring 33.

10 After that particular ring has been ground to the desired degree the expansive force of the ring will cause it to contact with the shell 30 at all times. After one ring is finished then the wheel 18 should be turned to move the main carriage to bring the next ring 33 to be ground into alignment with the notch 47, after which the second ring may be ground in like manner as the first; and these operations are repeated until all of the rings are ground in that head.

15 Prior to, and during the time any one of the rings 33 is being ground, and after they are ground, they will at all times contact with the shell 30, by reason of the inclination of the rings to expand.

20 It has been found by actual tests that piston-rings which have been fitted and ground in the manner above set forth give better results in practice, as each ring is ground to the position where it is to operate.

25 It is to be understood that I am not to be limited to the particular type of lathe con-

struction herein shown, neither am I limited to the several details of construction set forth, but various changes may be made therein as desired to meet varying conditions which may transpire.

Having now fully shown and described my invention and the best means for its construction and operation to me known at this time, what I claim and desire to secure by Letters Patent of the United States, is—

30 A piston ring grinding attachment for lathe carriages comprising a yoke having feet adapted to rest on and be adjustably secured to the side rails of a lathe carriage said yoke being provided with shell receiving opening having axial alignment with the head and tail stock of the lathe, a piston receiving shell removably held in said yoke and provided with a narrow lateral aperture wherethrough the edge of a grinding disk may pass, and grinding means adjustably supported by said lathe carriage, and including a base, means to feed the base across the carriage, a shaft supported revolvably on the base in parallelism to the axis of the shell, a grinding disk carried by the shaft and movable by the feed means into and out of said aperture, and means to drive said shaft.

35 In testimony whereof I have hereunto subscribed my name to this specification.

WILLIAM B. CLOSE.
